DETACHABLE ARM SHIELD FOR GARMENTS

Josephine Hamlin, Cold Spring Harbor, N. Y.

Application October 9, 1942, Serial No. 461,425

3 Claims. (Cl. 2—56)

This invention relates to new and useful improvements in a detachable arm shield for garments.

More particularly, the invention proposes a new arm shield which is characterized by an improved means for attaching and holding it in position on a garment.

More specifically, the invention proposes several forms of the improved holding means which are characterized by spear type fastening devices mounted on certain faces of the shield or on strips depending from certain points of the shield, which will become clear as this specification proceeds.

Another object of the invention is the construction of a device as mentioned which is simple and durable and which may be manufactured and sold at a reasonable cost.

For further comprehension of the invention, and of the objects and advantages thereof, reference will be had to the following description and accompanying drawing, and to the appended claims in which the various novel features of the invention are more particularly set forth.

In the accompanying drawing forming a material part of this disclosure:

Fig. 1 is an illustration of a blouse with detachable arm shields constructed in accordance with this invention.

Fig. 2 is a fragmentary enlarged sectional view taken on the line 2—2 of Fig. 1.

Fig. 3 is a fragmentary sectional view taken on the line 3—3 of Fig. 2.

Fig. 4 is a perspective view of the new arm shield.

Fig. 5 is an elevational view of the spear type of fastening device.

Fig. 6 is an elevational view of a detachable arm shield constructed in accordance with a modified form of this invention.

Fig. 7 is a perspective view of another arm shield constructed in accordance with still another form of this invention.

Fig. 8 is a fragmentary sectional view taken on the line 8—8 of Fig. 7.

The detachable arm shield for garments, in accordance with this invention, includes a pair of crescent shaped sections 10 secured together along their concaved sides 11. Spear type fastening means 12 is mounted on the adjacent faces of the points of said sections 10 for engaging through the armpit seams 13 of a waist or dress 14. Depending strips 15 from the centers of the convexed sides 16 of the said sections 10 are provided with spear type fastening devices 12 on

their extremities for engaging through the side seams 17 of said waist or dress 14.

Each spear type fastening device 12 includes a socket portion 18 which is mounted on one part 5 and is cooperative with a stud section 19 mounted on the other parts. These parts are adapted to engage each other when the fastener is closed. The stud part 19 is provided with a pointed end 20 which is capable of piercing the material of a seam when the fastener is applied. The strips 15 may comprise a strap bent at its center and secured at the bent portion with stitches 21 to the material of the sections of the shield. The free ends of this strap is provided with spear type fastener devices 12 as previously explained.

The arm shield is used by engaging it within the arm of a dress or waist in a manner so that the crescent shaped sections 10 straddle the armpit of the arm opening of the dress or waist. 10 The spear type fastening means 12 is pierced through the armpit seam 13 and the spear type fastening devices 12 upon the ends of the strips 15 are pierced through the side seams of the dress 15 for securely holding the shield detachably in position.

In Fig. 6 a modified form of the invention has been disclosed which is similar to the prior form, distinguishing merely in the fact that auxiliary strips 15 are used in lieu of the spear type fastening devices on the adjacent faces of the points of the sections 10 of the shield. These auxiliary strips 15 are provided with spear type fastening devices 12 which are adapted to engage through the armpit seams of the dress or waist. In other respects this form of the invention is identical to the previous form and like parts are identified by like reference numerals.

In Figs. 7 and 8 still another form of the invention is shown which is very similar to the 40 first form, distinguishing in the fact that the strips 15 have been eliminated and in their place the sections 10 have been provided with gussets 25 projecting at right angles from the sections at the centers of the convexed sides thereof. 45 These gussets 25 are set into the material of the sections 10 and are secured in position by the stitches 26. Each gusset 25 is of triangular shape and has opposed layers 27 and 28. These opposed layers are provided with a spear type fastening device 12.

This new arm shield is engaged across the armpit of a dress or waist. The spear type fastening devices 12 on the adjacent faces of the points of the sections 10 are clipped on to the armpit seam. The gussets 25 are engaged over the side

seams and the layers 27 and 28 thereof are forced together to engage the fastening means 12 thereof on to the side seam.

While I have illustrated and described the preferred embodiments of my invention, it is to be understood that I do not limit myself to the precise constructions herein disclosed and the right is reserved to all changes and modifications coming within the scope of the invention as defined in the appended claims.

Having thus described my invention, what I claim as new, and desire to secure by United States Letters Patent is:

1. A detachable arm shield for garments comprising a pair of crescent shaped sections secured together along their concaved sides, spear type fastener devices mounted on the adjacent faces of the points of said sections for engaging through the armpit seams of a dress or waist, the convexed sides of said sections being provided with gussets which project at right angles to these sections, said gussets having opposed layers, and spear type fastening devices on said opposed layers for engaging through the side seams of a dress.

2. A detachable arm shield for garments com-

prising a pair of crescent shaped sections secured together along their concaved sides, spear type fastener devices mounted on the adjacent faces of the points of said sections for engaging through the armpit seams of a dress or waist, the convexed sides of said sections being provided with gussets which project at right angles to these sections, said gussets having opposed layers, and spear type fastening devices on said opposed layers for engaging through the side seams of a dress, said gussets being of triangular shapes.

3. A detachable arm shield for garments comprising a pair of crescent shaped sections secured together along their concaved sides, spear type fastener devices mounted on the adjacent faces of the points of said sections for engaging through the armpit seams of a dress or waist, the convexed sides of said sections being provided with gussets which project at right angles to these sections, said gussets having opposed layers, and spear type fastening devices on said opposed layers for engaging through the side seams of a dress, said gussets being stitched to said crescent shaped sections.

JOSEPHINE HAMLIN.
